UNITED STATES PATENT OFFICE.

ROSS HALL, OF MILLERSBURG, OHIO.

STOVE, &c.

SPECIFICATION forming part of Letters Patent No. 236,827, dated January 4, 1881.

Application filed May 6, 1880. (No model.)

To all whom it may concern:

Be it known that I, ROSS HALL, of Millersburg, in the county of Holmes and State of Ohio, have invented certain new and useful 5 Improvements in Stoves; and I do hereby declare the following to be a full, clear, and exact description of the same.

The object of my invention is an improvement in the class of coal-stoves having a reservoir or feeder attached exteriorly, and which is so arranged that the coal is fed into the lower part of the fire-pot or combustion-chamber, so that the combustible gases evolved by heat from the coal that fills the lower part of 10 the chamber will pass up into the mass of incandescent coal which fills the upper portion of such chamber, and thereby become consumed and add to the aggregate amount of heat developed from the coal. Thus the gases 15 which are unconsumed, and thereby wasted, in reservoir-stoves of the usual construction are utilized.

My improvement pertains particularly to the construction and combination of parts, as 20 hereinafter described and claimed.

In the drawings forming part of my specification, Figure 1 is a vertical central section, on line *x x*, Fig. 2, of a stove embodying my invention. Fig. 2 is a vertical section on line 25 *y y*, Fig. 1. Fig. 3 is a perspective view of the stove. Figs. 4, 5, and 6 are detail views, and Figs. 7 and 8 show the application of my improvement to a boiler-furnace and cooking-stove, respectively.

The stove A has a fire-pot, *a b c*. The coal-reservoir B is attached to the lower part of the stove exteriorly, so that coal is fed or delivered into the combustion-chamber or fire-pot at or near the bottom. Reservoir or magazine B is provided with a hinged lid or cover, D, having a plate, E, which is hinged to the under side of the latter, so that when the cover is opened said plate will assume an inclined position (dotted lines, Fig. 6) over the joint of the same cover, and thus not only prevent coal-dust from entering the joint, but also aid in deflecting and guiding the stream of coal into the magazine when it is being filled. When the door is closed the plate E automatically assumes a pendent position within the magazine, as shown in Fig. 6.

In order to prevent the undue radiation of heat from the stove proper, A, upon the magazine B, I interpose a fender-plate, F, which is

suspended from the dogs *e*, which form part of 55 the devices that attach the magazine to the stove.

The lower part, *d*, of the magazine B is provided with flanges *f*, which enter grooved guides *g*, cast on the back of the stove. These 60 guides are continued on three sides, but wanting on the fourth, so that the magazine may be attached and detached by sliding it laterally, as will be readily understood. When attached as shown, it may be held fixed in place 65 by a thumb-screw, *h*, Fig. 3.

The dogs *e* are in the form of staples, and their arms enter keepers or sockets *i*, formed on the respective opposite sides of the stove and magazine. 70

To remove the magazine the dogs or staples *e* are raised and drawn out of the keepers *i*, the screw *h* removed, and the magazine may then be slid laterally out of the grooves.

It is also apparent that the fender-plate F 75 may be readily removed along with the magazine B, since it is suspended from the dogs *G*, that pass through holes in the plate. I do not broadly claim the employment of such plate for the purpose hereinbefore specified. 80

The holes *K* in the lower part of the magazine B allow insertion of a poker to facilitate or hasten feeding the coal downward into the fire-pot. The holes are shaped as shown in Figs. 2, 4, and 5, and provided with pivoted 85 drop-covers *l*.

What I claim is—

1. The combination, with the stove A, magazine B, and the detachable dogs *e*, which connect them at the upper end, of the fender- 90 plate F, which is suspended from said dogs and made detachable, as shown and described.

2. The combination, with the stove A, having flanges *g* and sockets *i*, of the detachable coal-reservoir B, having flanges *f*, and the 95 dogs *e*, all as shown and described.

3. The combination, with the hinged magazine or reservoir cover, of the coal-deflecting and joint-protecting plate, which is hinged thereto, substantially as shown and described, 100 to adapt it to operate as specified.

The above specification of my invention signed by me.

ROSS HALL.
